Patented Oct. 30, 1923.

UNITED STATES PATENT OFFICE.

PAUL R. PUCKETT, OF ATLANTA, GEORGIA.

CONTAINER.

Application filed April 5, 1922. Serial No. 549,698.

To all whom it may concern:

Be it known that I, PAUL R. PUCKETT, a citizen of the United States, residing at Atlanta, in the county of Fulton and State of Georgia, have invented new and useful Improvements in Containers, of which the following is a specification.

This invention relates to receptacles and has for one of its objects the provision of a device which is fashioned to serve as a container for merchandise of a certain class, and having additional features of structure associated therewith, to adapt it, after fulfillment of its function as a container of said merchandise, to subsequent uses in connection with articles or merchandise of a different class or character.

More specifically the object of the invention is the construction of a can having a removable cover, said can and cover forming a complete container within which an article of merchandise may be packed, in combination with another element, serving as a filler to occupy surplus space within said container during the functioning of the latter as a receptacle for said article of merchandise, but being adaptable to other uses after the can has been emptied of its original contents.

A still more specific object of the invention is the provision of a can having removable covers at both ends, primarily functioning as a shipping container, for an article of merchandise, and a series of auxiliary devices selectively cooperable with said can, for performing a variety of functions foreign to the original use of the can as a shipping receptacle.

Another object of the invention is to provide a novel method of merchandising which involves the sale of an article of merchandise in a container, and the exploitation of said container by distribution at the place of sale of said merchandise, of auxiliary devices cooperable with said container for adapting it to a variety of uses when the article of merchandise has been removed therefrom.

With the above and other objects in view, my invention consists in the improved container illustrated in the accompanying drawings, described in the following specification, and particularly claimed, and in such variations and modifications thereof as will be obvious to those skilled in the art to which my invention relates.

In the drawing accompanying and forming a part of this specification, and wherein the preferred embodiment of my invention is illustrated:—

Figure 1 is a perspective view of the container of my invention, a portion thereof being broken away to show the merchandise therein enclosed.

Figure 2 is a perspective view of the same container emptied of its contents with the top cover removed and a portion of the front broken away to show the interior.

Figure 3 is a perspective view of the same container, equipped as a flash-light.

Figure 4 shows two views of a circuit breaker which may be used in the assemblage of elements shown in Figure 3, to form a flash-light.

Figures 5, 6, 7, 8 and 9 show respectively two forms of funnel shaped reflectors, a screw cover with an opening in the top, a glass lens, and a circular perforated disk of the same diameter as the container.

Figure 10 represents the lower cover of the container.

Figure 11 is a perspective view of the elements shown in Figures 7 and 8 in assembled relation.

Figure 12 is an obverse view in perspective of the screw cap shown in Figure 7.

Figure 13 is a diametrical cross sectional view of the perforated disk shown in Figure 9.

Figure 14 shows the arrangement of parts, adapted to function as a funnel.

Figure 15 is a perspective view of the container arranged to hold small objects so that they will not readily be spilled.

Figure 16 is a perspective view of the container arranged to form a dispensing device for small articles.

Figure 17 is a view of one end of the container with the elements shown in Figures 7, 8 and 9 assembled thereon to form a dimmed flash-light.

Figure 18 is a detail view of the lower end of the container with the elements shown in Figures 7 and 9 applied thereto with the rough surface downward forming a buffer for roughening an inner tube.

Figure 19 is a similar view in which the smooth side of the disk shown in Figure 9 is placed outwardly and forming a sifter for spraying insecticides upon plants.

Referring now in detail to the several figures, the numeral 1 represents a cylindrical

tubular member or casing which may be made of metal, pasteboard or any other suitable substance which is preferably formed with a screw thread pressed in its upper and 5 lower ends as shown at 2 and 3 in Figure 2, for the reception of the screw covers 4 and 5 of which one is provided for each end. The can, as thus described, is old in the art and no claim is made thereto except in combination with the other novel features which will be hereinafter described. The preferred class of merchandise which is packed in said container is a roll 6 of patching rubber, which is wrapped around a collapsible 15 tube 7 of rubber cement. It is of course obvious that any other class of merchandise may be packaged in the container without conflicting with the spirit and substance of the invention.

20 In order to give the container a value apart from that of the goods therein enclosed and thus to enhance the desirability of purchase of the packaged article of merchandise, I have provided means for giving an intrinsic value to the container itself, by adapting it to many uses in the hands of a purchaser after the merchandise has been removed therefrom, instead of being thrown away as is the usual practice. These means 25 comprise certain inexpensive attachments which may be packed in the container or which it is contemplated to distribute, gratis, along with the packaged goods at the time of sale, or which may be purchased at 30 a nominal price, preferably at the place where the said goods are sold, and by means of which the container may be converted at will, into one or a number of useful articles.

35 In Figure 1, for instance, will be observed a funnel shaped member 8 retained in the upper end of the container between the tubular member 1 and the screw cover 4. This member is apertured at its lower end and screw threaded to fit the base of the small 40 electric bulb of a flash-light, such as is shown at 17 in Figure 3, and it is preferably bright or polished on the inside, adapting it to use as a reflector. When the packaged article is sold this member is in place as 45 shown in Figure 1, and serves as a spacing element or filler to keep the article of merchandise within said container from excessive longitudinal movement therein. When 50 the container is empty the member 8 may be used as a funnel by removing the lower screw cover 5 from the container and by substituting for the closed screw cover 4 at the top the screw-cap 9 shown in Figure 7 which has a circular opening in the top surrounded by the flange 10. This flange, cooperating 55 with the upper edge of the tubular member 1 holds the funnel shaped member 8 in position and permits the pouring of liquids therethrough and through the bottom of the 60 container.

65 By screwing on the lower cover 5 as shown in Figure 15 a receptacle may be constituted, the funnel shaped member 8 forming a trap-like entrance into which small objects 70 may be dropped but from which they will not readily be spilled, should the receptacle be overturned. The receptacle shown in Figure 15 may be quickly emptied by removing the lower screw cover 5.

75 The upper screw cover 4 may if desired be removed from the receptacle as shown in Figure 14 and the funnel shaped member 8 placed against the lower end of the tubular member 1, and held in position by means of the open-topped screw-cap 9. This forms a 80 convenient means for filling bottles with liquids or supplying water to a storage battery.

85 Should the possessor of one of the containers desire to convert it into a flash-light it is necessary only for him to arrange the funnel shaped member 8 and the opened-topped screw-cap 9 at the upper end of the container, and to provide a couple of flash-light batteries, holding the latter in place 90 by means of one of the metallic strips 11 or 12 shown in Figure 1. One of these strips is shown in assembled relation in Figure 3 and includes an angular portion resiliently holding the batteries together, the upper 95 end of said strip making contact with a light bulb and the angular portion adapted to coact with the lower screw cover 5 forming a switch by means of which the flash-light is illuminated or extinguished by 100 screwing said cover on or off a portion of a turn. If all the parts shown in Figure 3 are metal, it is obvious that the batteries will be short circuited when the switch is closed, to prevent which it is necessary that some 105 means be provided for insulating the light bulb from the metallic parts of the container. This means may take the form of funnel shaped member 13 shown in Figure 5, which has a packing of insulation 14 between the light bulb and funnel shaped member. In assembling the package, care will be taken that in all-metal cans the form 110 13 shall be provided while in cans the tubular portion of which is made of pasteboard, the form of funnel-shaped member shown in Figure 6, is furnished in which there is no insulation present.

115 In assembling the container and its parts for a flash-light, it is desirable to use a lens such as shown at 15 in Figure 8. This lens is placed upon the funnel shaped member 8 and held in place by the open-topped screw-cap 9. It is sometimes desirable to 120 dim the flash-light, for instance in its use in sick rooms. In this case the perforated disk 16 shown in Figure 9 is placed upon the end of the tubular member 1 beneath the lens 15, both members being held in place 125 by the open-topped screw-cap 9. This 130

serves as an efficient dimmer for the flash-light, by permitting the radiation of only those rays which find their way through the perforations in the disk 16.

5 In Figure 16 is shown the use of the container as a dispenser of small articles in which the funnel shaped member 8 is secured to the lower end thereof and the top portion closed by means of the screw cover 10 4. This form of device is convenient for delivering small objects, one at a time, such as matches or metallic parts used about a garage.

Figures 18 and 19 suggest other uses of 15 the container in combination with the perforated disk 16. As will be noted in Figure 13 the perforations in this disk are brought about by punching through the metal, the bur which projects from the 20 lower side thereof constituting a rough surface or buffer. This is shown facing outwardly in Figure 18, adapting the container to use as a buffer or roughener for any class of work. In this figure the suggested use 25 is that of roughening an inner tube before applying a cold patch thereto.

Figure 19 shows the use of the container as a sifter or sieve for dusting insecticides upon plants or for sifting talcum powder 30 within tire casings. In this arrangement the disk 16 is placed with either smooth or rough surface outwardly and the funnel shaped member 8 is preferably positioned with the small end upward in the lower 35 end of the tubular member 1 so as to control the discharge of powder and avoid waste, or use of an excessive quantity thereof.

These are only a few of the uses and 40 combinations which may be worked out with the simple auxiliary devices disclosed in the several figures or other devices of the same generic character which may be from time to time brought out.

It will be readily appreciated that the 45 several devices illustrated in Figures 4 to 9 inclusive are simple in character and can be produced at a nominal cost compared with the cost of the packaged merchandise, and that they can be readily supplied to the 50 retailer for gratuitous distribution in sets with each package of merchandise sold, or may be kept on hand, to be sold to the user of the merchandise at a small cost, thus putting into operation a novel method of 55 merchandising in which the subsequent value of the container is exploited to such an extent that the desire to possess a container will be a material inducement to the sale of the packaged article.

60 It will be understood that various changes may be made in the form and relation of parts to suit different requirements of use,

and that the invention, therefore, is not limited to the precise details of construction and arrangement shown.

Having described my invention what I claim as new and desire to secure by Letters Patent is:—

1. A container functioning primarily as a shipping receptacle for an article of merchandise, comprising a casing having an open end, and a member detachably fitting said end and normally extending within said casing, functioning as a filler to prevent excessive endwise movement of said article of merchandise, and being adapted to cooperate with said container after the removal of the merchandise therefrom, to adapt said container to additional uses foreign to its primary function as a shipping receptacle.

2. A container functioning primarily as a shipping receptacle for an article of merchandise, comprising a casing having an open end, a plurality of auxiliary devices for said container, each substantially fitting the end of said casing and selectively applicable thereto, singly or in groups, and means engageable with said casing and with said device or group of devices, for clampably holding them to said tubular member.

3. A container functioning primarily as a shipping receptacle for an article of merchandise, comprising a tubular member having an open end, a plurality of auxiliary devices for said container, each having substantially the same diameter as said tubular member and selectively applicable to the open end thereof, singly or in groups, and means engageable with said tubular member and with said device or group of devices, for clampably holding them to said tubular member.

4. A container functioning primarily as a shipping receptacle for an article of merchandise, comprising a tubular member having removable closures at the ends thereof and a funnel-shaped centrally apertured member in one end thereof functioning as a filler to prevent excessive endwise movement of said article of merchandise in said container, said funnel-shaped member being adapted to cooperate with said container after removal of said merchandise therefrom, to adapt said container to additional uses foreign to its primary function as a shipping receptacle.

In testimony whereof I have hereunto set my hand in presence of two subscribing witnesses.

PAUL R. PUCKETT.
